UNITED STATES PATENT OFFICE

JALMER KNUDSON, OF MINNEAPOLIS, MINNESOTA

LOCOMOTIVE NOZZLE RESTRICTOR

Application filed May 23, 1927. Serial No. 193,544.

This invention relates to a nozzle controlling or restricting device and particularly to such a device adapted for use on locomotives. As is well known to those skilled in the art, 5 a nozzle is used below the smokestack of a locomotive, through which the exhaust gases pass to produce the desired draft. There is not always the same amount of steam passed through the cylinders and it is quite desirable in order to properly regulate the draft 10 on the fire, to be able to control the opening through the nozzle. In the control of modern locomotives, the reverse lever is usually used and when this lever is thrown to its 15 extreme position, it is desirable to have the exhaust nozzle least restricted. It is also desirable to have a restricted nozzle when the engine is running at uniform speed with the reverse lever in central position or running 20 position, so that the velocity of the exhaust gases will be somewhat increased.

It is an object of this invention, therefore, to provide a very simple and convenient means by which the nozzle may be restricted 25 to afford the desired draft under various running conditions.

It is another object of the invention to provide a means for restricting or controlling the exhaust nozzle to regulate the draft, 30 which means is connected to the reverse lever of a locomotive and is adjusted when the reverse lever is moved.

It is more specifically an object of the invention to provide a controlling means for 35 the exhaust nozzle of a locomotive comprising a circular plate of much less diameter than the diameter of said nozzle, which plate is swingably mounted adjacent the top of the nozzle to be moved into and held in various positions to more or less restrict the opening 40 through the nozzle.

These and other objects and advantages of the invention will be fully set forth in the 45 following description made in connection with the accompanying drawings, in which like reference characters refer to similar parts throughout the several views and in which:—

Fig. 1 shows a view in side elevation of a 50 portion of the locomotive, certain parts being

broken away to more clearly show the apparatus;

Fig. 2 is a horizontal section taken on line 2—2 of Fig. 1, as indicated by the arrows;

Fig. 3 is a vertical section taken on line 3—3 of Fig. 2, as indicated by the arrows; and

Fig. 4 is a plan view of the nozzle restricting means and the operating shaft and gear therefor.

Referring to the drawings, in Fig. 1 part of a locomotive is shown, of which it will only be necessary to consider the boiler 5, the stack 6, the cabin 7 in which is disposed the reverse or control lever 8, said lever being moved along a quadrant or segment 9 arranged to hold the same in various positions. The valve controlling lever 10 is shown as mounted in the rear of the cross-head on a bearing 11 which is connected to the valve 70 operating lever 12, the latter being connected to the valve by the valve rod 13. The valve controlling lever 10 is shown connected to the lever 8 in the usual manner by a link 14.

The exhaust nozzle of the locomotive is shown as 15 and the same is provided with a rod 16 extending diametrically thereof and journaled in the sides of said nozzle. The rod 16 carries centrally of the nozzle 15 a circular plate 17 disposed substantially coaxial with the nozzle 15. The rod 16 extends to one side of the nozzle 15 and has secured to the end thereof a pinion 18. The pinion 18 meshes with a gear segment 19 mounted on a shaft 20 journaled at one end in the side of the nozzle 15 and adjacent its other end in the boiler shell 5. The shaft 20 has an arm 21 secured thereto and a link 22 is secured to the end of arm 21 and extends rearwardly, being pivotally secured at its other end to the upper end of the valve controlling lever 10.

In operation when the reversing or controlling lever 8 is thrown to one of its extreme positions as indicated in Fig. 1, the link 22 will be moved to swing arm 21 so that the circular plate 17 will be substantially in vertical position. The nozzle will then be the least restricted and will have substantially its full opening. At this time considerable

steam will be admitted to the cylinders and a sufficient opening will thus be provided for this steam. The extra amount of steam will give a sufficient velocity to the exhaust gases so that the desired draft will be produced. When the lever 8 is thrown to an intermediate position where it is usually disposed when the engine is running at uniform speed, the arm 21 will be swung and shaft 16 moved through gears 19 and 18 so that the plate 17 will be disposed more nearly in a horizontal position, thus restricting the opening of the nozzle. The restricted opening will tend to increase the velocity of the exhaust gases from the cylinder and the desired draft will thus be obtained while the engine is running at uniform speed and with a smaller supply of steam. The plate 17 tends to spread the steam issuing from the nozzle 15 and the steam passes upwardly into the stack 6 substantially filling the stack. If the steam is not so spread when the steam is partially shut off at the throttle, the steam tends to pass in a central stream through the stack 6 and air is drawn down around the sides of the stack by the vacuum formed in the exhaust chamber or front end of the boiler 5. This entering air destroys the vacuum caused by the outgoing steam and spoils the draft through the fire box. If the steam is spread by the plate 17 it prevents this entry of air when the engine is working with the steam partly shut off. It will be seen that the control of the member 17 is thus really automatic or follows the movements of the lever 8.

From the above description it is seen that applicant has provided a very simple and efficient nozzle controlling device. The nozzle is controlled so that the desired velocity of the steam and the desired draft are obtainable at all times and the adjustment is made without any special attention from the engineer or fireman. The device is quite simple and can be easily and quickly installed on standard locomotives with very little change therein. The device has been amply demonstrated in actual practice and found to be very successful and efficient.

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims.

What is claimed is:—

1. In a locomotive structure, an exhaust nozzle, a circular plate disposed at the upper portion of said nozzle, a rod passing centrally across said plate and secured thereto, being journaled in the sides of said nozzle, gear means at the outer side of said nozzle for oscillating said member, and means connected

to said last mentioned means and extending to the cab of the locomotive, for operating said gear means, whereby said member may be disposed in a plane substantially at right angles to the axis of said nozzle or in a substantially vertical plane for regulating the flow of said gas through said nozzle.

2. In a locomotive structure, an exhaust nozzle, a stack disposed above and spaced from said nozzle, means disposed in said exhaust nozzle, an appreciable distance below the top of the same adapted to be positioned to have said nozzle unobstructed or to be more or less obstructed at the central portion to spread the steam passing through said nozzle, said steam being directed by said nozzle into said stack whereby said stack will be substantially filled with steam whether a greater amount or a lesser amount of steam is passing through said nozzle.

In testimony whereof I affix my signature.

JALMER KNUDSON.
